 Lee Wilson Sales Corporation, Cleveland, Ohio,
 a corporation of Ohio

Application November 15, 1938, Serial No. 240,498

4 Claims. (Cl. 126—91)

This invention relates in general to heating, and in particular to a heating element particularly adapted for installation in furnaces, although it may be utilized in other applications.

Various types of indirect heaters for furnaces and the like have been proposed heretofore. It is an object of this invention to improve generally upon such devices and, in particular, to provide a radiant heating element adapted to be heated by the combustion of fuel, which is simple, sturdy, and relatively inexpensive in construction and efficient in operation. In a preferred form, the heating element of my invention comprises a radiant tube of generally flattened character having a baffle extending thereto dividing the tube into a pair of passages. Inlet and outlet ports are provided adjacent one end of the tube and a burner is provided for the inlet port. The burner supplies a combustible mixture of fuel and air to one of the passages along the tube for combustion therein to heat the latter to radiant temperature. After passing along the length of the tube in one direction, the gases sweep around the end of the baffle and return the full length of the tube in the other direction. Conveniently, the baffle may be in the form of a pipe for supplying secondary air to the combustion products at a point spaced from the burner.

The following detailed description of the invention refers to the accompanying drawings illustrating the aforementioned embodiment as applied to a typical installation. In the drawings:

Fig. 1 is a longitudinal central section through a furnace having heating elements of my invention mounted therein;

Fig. 2 is a transverse sectional view taken along line II—II of Fig. 1; line I—I of Fig. 2 illustrates the plane on which the section of Fig. 1 is taken;

Fig. 3 is a sectional view taken along the line III—III of Fig. 2 with parts omitted; and

Fig. 4 is a transverse sectional view taken along the plane of line IV—IV of Fig. 3.

Referring now in detail to the drawings and, for the present, to Figs. 3 and 4 particularly, a heating element embodying my invention, indicated generally at 10, comprises a tube 11 which, as shown, is preferably corrugated to increase its rigidity. The tube may be of relatively light gauge metal and is preferably composed of a heat-resistant alloy. As shown in Fig. 4, the width of the tube 10 is several times its thickness, the section of the tube being of oval shape.

A casting 12 is welded to one end of the tube and is provided with an inlet port 13 and an exhaust port 14. The casting 12 also has a port 15

for the reception of a baffle pipe 16 extending into one end of the tube 11 and terminating just short of the other end. As shown in Fig. 4, the pipe 16 serves as a baffle dividing the tube 11 into lower and upper chambers 17 and 18. While the pipe 16 is spaced slightly from the side walls of the tube 11, permitting some by-passing of combustion gases from the lower passage 17 to the upper passage 18, the major volume of the gases will be compelled to travel the length of the passage 17 before entering the passage 18.

A return bend casting or closure 19 is welded into the end of the tube 11 opposite that to which the casting 12 is secured.

Considering now more particularly Figs. 1 and 2, illustrating a typical installation of heating elements according to my invention, an enameling furnace or the like 20 has side walls 21, a hearth 22 and a roof 23 assembled within a structural framework including buckstays 24. One end wall 20 25 of the furnace has a charging opening 26 therein adapted to be opened and closed by a door (not shown).

Heating elements 10 are mounted on the side walls 21 and the hearth 22, being supported thereon by brackets 27. The inlet and exhaust ports of the heating elements are disposed adjacent the end wall 28 of the furnace, inlet and exhaust pipes 29 and 30 extending from said ports and through the end wall 28. A burner 31 is positioned in each of the inlet pipes 29 and is connected by piping, as shown in Fig. 1, to a suitable source of fuel or combustible mixture of fuel and air (not shown). The baffle pipes 16 of all the heating elements are connected to an air supply header 32 which is in communication with a supply of air under low pressure such as a blower (not shown).

The exhaust pipes 30, leading from all the heating elements, are in communication with an exhaust duct 33 which may be connected to a stack if natural draft is relied on, or to a suitable exhaust fan or ejector if forced draft is desired.

It will be apparent from the foregoing description that the burners 31 supply a combustible mixture to the passages 17 of the heating elements 10 for combustion therein and that the resulting products of combustion flow for the most part along the length of the passages 17, around the end of the baffle pipes and return along the passages 18 to the exhaust pipes 30 and duct 33. As already stated, some small portion of the gases is by-passed from the passages 17 to the passages 18 around the baffle pipes 16. The tubes 11 of the heating elements 10

10 are heated to radiant temperature by the hot combustion gases and radiate heat to material deposited within the furnace. All joints in the heating elements are made gas-tight so that the combustion gases are confined without possibility of contact with the material in the furnace.

5 The structure of the heating elements 10 is quite simple and relatively inexpensive. At the same time, a high degree of thermal efficiency 10 may be obtained therewith because of the long path of travel provided for the major part of the combustion gases in the tubes 11. The introduction of secondary air at points remote from the burners, furthermore, also increases the efficiency of combustion.

15 While I have illustrated and described herein but one form of heating element and but one typical installation thereof, it will be understood that changes in the construction disclosed 20 and the manner of utilizing it may be made without departing from the spirit of the invention or the scope of the appended claims.

I claim:

25 1. A radiant heating element comprising an elongated sheet metal tube, one dimension of the transverse section of the tube being several times

the other dimension, a cap at one end of said tube, a closure at the other end of the tube having inlet and outlet ports on opposite sides of the central plane therethrough and a substantially central port, a pipe extending through said central port, terminating short of said cap and serving as a secondary air conduit, said pipe being of such size relative to said other dimension as to constitute a baffle defining entering and return passages for combustion gases and substantially 10 restricting flow of such gases from the entering passage to the return passage except by a path around the end of said pipe.

2. A radiant heating element as defined by claim 1 characterized by said cap and closure 15 having a wall thickness greater than that of said tube.

3. A radiant heating element as defined by claim 1 characterized by said tube having a section of substantially oval shape.

20 4. A radiant heating element as defined by claim 1 characterized by said cap and closure being castings having a wall thickness greater than said tube.

JAMES C. WOODSON. 25
